UNITED STATES PATENT OFFICE.

ROBERT D. EVANS, OF WILKINSBURG, PENNSYLVANIA, ASSIGNOR TO WESTINGHOUSE ELECTRIC & MANUFACTURING COMPANY, A CORPORATION OF PENNSYLVANIA.

CIRCUIT-INTERRUPTING DEVICE.

1,314,581.

Specification of Letters Patent. Patented Sept. 2, 1919.

Application filed September 16, 1918. Serial No. 254,219.

To all whom it may concern:

Be it known that I, ROBERT D. EVANS, a citizen of the United States, and a resident of Wilkinsburg, in the county of Allegheny 5 and State of Pennsylvania, have invented a new and useful Improvement in Circuit-Interruption Devices, of which the following is a specification.

My invention relates to circuit interrupting devices and particularly to vacuum-electric apparatus for interrupting direct-current circuits.

One object of my invention is to provide an automatic circuit interrupter having no 15 movable parts.

A further object of my invention is to provide a device, of the above-indicated character, that shall be simple and inexpensive to construct and effective in its opera- 20 tion.

In practising my invention I provide a vacuum-electric apparatus, such as a mercury vapor valve or converter, and a transformer having two opposing windings of 25 preferably different numbers of turns that are connected in series on opposite sides of the valve. A condenser is connected in shunt relation to the valve and the winding having the less number of turns. When a short circuit or other disturbance occurs on the system to which the device is connected the quick change in current incident thereto causes current to be shunted through the condenser to the winding having the larger 30 number of turns. This causes the current through the other winding to be still further reduced by reason of the opposing actions of the windings, and, since the valve is connected in series with the winding hav- 35 ing the less number of turns, its arc will be extinguished to thereby interrupt the circuit.

The single figure of the accompanying drawing is a diagrammatic view of an electric circuit embodying my invention.

A direct-current circuit 1 comprises, in general, a generator 2 or other source of electromotive force, an interrupting device 3 and a load 4.

The interrupting device 3 comprises a vacuum-electric apparatus 5, such as a mercury-vapor valve or converter, a transformer 6 having a primary winding 7 that is con-

nected in series with the valve 5 on one side thereof and a winding 8 that is connected in series with the valve 5 on the other side thereof. The winding 8 has a larger number of turns than the winding 7 and is so connected that it opposes the flow of the current through the winding 7. A condenser 9 is connected in shunt relation to that portion of the circuit 1 comprising the winding 7 and the valve 5.

When a short circuit or ground occurs on the circuit 1 the current traversing the circuit will quickly change to cause current to be shunted through the condenser 9 around the winding 7 and the valve 5. Thus, the current that is shunted around the valve 5 and the current traversing the valve will 70 traverse the winding 8 which will induce a counter electromotive force in the winding 7 to thereby reduce the current traversing the same and the valve 5. If this current is reduced to a predetermined relatively low 75 value the arc of the valve 5 will be extinguished and since, under normal conditions, the direct current from the source 2 of electromotive force will not traverse the condenser 9, no current will be supplied 80 to the load 4 after the arc is extinguished.

My invention is not limited to the specific apparatus illustrated as it may be variously modified without departing from the spirit and scope of the invention as set forth in 85 the appended claims.

I claim as my invention:

1. In a direct-current circuit, the combination with a vapor valve therein, of a transformer, a condenser, and means for so connecting the windings of the transformer in series with the valve and the condenser in shunt to the valve and one winding of the transformer that, when the current traversing the circuit changes quickly, sufficient 95 current will be shunted from the valve to extinguish its arc.

2. In an electric circuit, the combination with a vapor valve, of a transformer the windings of which are connected in series 100 with the valve, and a condenser connected in shunt relation to one of the windings and the valve, said windings being so connected that one opposes the other.

3. In an electric circuit, the combination 105 with a vapor valve, of a transformer the

- windings of which are connected in series with the valve, and a condenser connected in shunt relation to one of the windings and the valve, said winding being adapted to reduce the current through the valve when the condenser discharges.
4. In an electric circuit, the combination with a vapor valve, of a transformer having two opposing windings connected in series with the valve, and means connected in shunt relation to the valve for providing a bypass for current around the valve and through one of the windings when the current traversing the circuit changes quickly.
10. 5. In a direct-current circuit, the combination with a vacuum-electric apparatus, of a transformer having two opposing windings connected in series with the said apparatus on opposite sides thereof, and means for shunting current from one winding and the said apparatus under predetermined conditions.
15. 6. In a direct-current circuit, the combination with a vacuum-electric apparatus, of a transformer having two opposing windings connected in series with the said ap-
- 20
- 25

paratus on opposite sides thereof, and a condenser for shunting current from one winding and the said apparatus under predetermined conditions.

30

7. In a direct-current circuit, the combination with a vacuum-electric apparatus, of a transformer having two opposing windings connected in series with the said apparatus on opposite sides thereof, and a condenser for shunting current from one winding and the said apparatus when the current traversing the circuit changes quickly.

35

8. In a direct-current circuit, the combination with a vapor valve, of a transformer having two opposing windings of different numbers of turns connected in series with the valve, and a condenser connected in shunt relation to the valve and the winding having the smaller number of turns for the purpose of increasing the current through the other winding under predetermined conditions.

40

In testimony whereof, I have hereunto subscribed my name this 4th day of Sept., 50 1918.

45

ROBERT D. EVANS.
